UNITED STATES PATENT OFFICE.

ROBERT P. JOHNSON, OF COLUMBUS, OHIO.

DESIGN FOR A PNEUMATIC TIRE.

Application filed February 21, 1927. Serial No. 20,844. Term of patent 7 years.

To all whom it may concern:

Be it known that I, ROBERT P. JOHNSON, a citizen of the United States, residing at Columbus, in the county of Franklin and State of Ohio, have invented a new, original, and ornamental Design for Pneumatic Tires, of which the following is a specification, reference being had to the accompanying drawing, forming part thereof.

Figure 1 is a plan view of a pneumatic tire, showing my new design, and

Figure 2 is a fragmentary vertical transverse sectional view thereof.

I claim:

The ornamental design for a pneumatic tire, as shown.

ROBERT P. JOHNSON.
